UNITED STATES PATENT OFFICE.

IRA ROBBINS, OF CAMDEN, NEW JERSEY, AND DAVID HESTON, OF PHILADELPHIA, PENNSYLVANIA, ASSIGNORS OF TWO-THIRDS TO DAVID HESTON AND ONE-THIRD TO IRA ROBBINS.

CHROMATIC PRINTING-PRESS.

SPECIFICATION forming part of Letters Patent No. 246,821, dated September 6, 1881.

Application filed July 15, 1880. (No model.)

To all whom it may concern:

Be it known that we, IRA ROBBINS, of the city and county of Camden, State of New Jersey, and DAVID HESTON, of the city and county of Philadelphia, State of Pennsylvania, and both citizens of the United States, have invented a new and useful Improvement in Chromatic Printing-Presses, which improvement is fully set forth in the following specification and accompanying drawings, in which—

Figure 1 is a side elevation of the printing-press embodying our invention. Fig. 2 is an end view thereof. Fig. 3 is a horizontal section of a portion thereof in line x x , Fig. 1. Fig. 4 is an enlarged view of a detached portion thereof.

This invention relates to printing-presses operating by flat pressure; and it consists, partly, in a platen having at its rear side laterally and rearwardly extending angular arms, in combination with arms attached to said rearward extensions and supporting the bed, all substantially as hereinafter set forth.

It also consists in the combination, with the bed of a printing-press, of an inking roller or rollers and a movable foot or roller support, and in further details of construction herein-after set forth and claimed.

Referring to the drawings, A A' A'' represent a number of bed and platen presses, which are mounted upon a common base-plate, B, and, excepting as far as is necessary for purposes of our invention, may be of well-known form and construction. The presses are adjustable on the base-plate, in order to be set nearer to or farther from each other, and the number of them employed is equal to the number of colors to be printed.

C represents the main or driving-shaft, which is mounted on the frame or support of one of the presses, (in the present case the right-hand press A,) and carries at one end a pinion, a, and a wheel, b. The pinion a gears with a larger pinion, d, whose shaft is mounted on the frame of the press A, and it will be noticed that the frames of the other presses have each mounted on them pinions and a wheel similar to a d b, as will be seen at a' d' b' and a'' d'' b''.

Each wheel b' b'' has a wrist-pin, e, to which is suspended freely a boss, D, and through the several bosses is passed a rod or bar, E, to which each boss is secured by means of a set-screw, f, the several bosses occupying the same relative positions one to another on the wheels b' b''.

To the end of the bar E are secured arms F, whose lower ends are connected to wrist-pins g on wheels G, the shafts G' whereof are mounted on the base-plate and carry on their opposite ends wheels G'', which are connected by a bar or rod, H, as shown in Fig. 2 and dotted lines, Fig. 1.

Attached to the wrist-pin of each of the wheels d' d'' is an arm, J, by which the bed K and connected mechanism of each press is raised and lowered, and to the frame or support of each press is pivoted an arm, J', which is connected to the mechanism moving the inking-rollers h over the inking-plate and form, features which are, however, well known.

It will be seen that the several presses are arranged one behind the other in close proximity to each other. In order to admit of the movement of one press close to the rear of the adjacent press, laterally-projecting angular arms J''' are formed with or secured to the rear of the bed of each press, and the arms J'', to whose upper ends the beds are hinged, are pivoted to said angular arms. This spreads the arms J'' in such manner that a space exists behind each press for the platen L, the arms J J', and bed K of the adjacent press, so that the presses may be operated without interfering one with another or adjacent movable parts striking each other. (See Fig. 3.)

The rear end of each bed has hinged to it a foot, M, which falls by gravity, but opens out to form an extension of the bed when the inking-rollers h reach the lower face of said foot, thus providing a proper support for the rollers at their lowest points. As soon as the rollers return the foot is no longer controlled and falls to an upright position, (see Fig. 4,) whereby the rollers of the adjacent press are provided with sufficient space for movements, and striking of the rear of the bed is prevented.

Suspended from a beam, N, attached to the ceiling or otherwise supported, are springs P, the lower end of each of which is connected to a proper part of one of the beds and expanded when the bed descends and permitted to contract when the bed ascends. By this provision a portion of the weight of the bed and connected parts is removed from the operating-arms and crank-shaft, and thus the press is balanced and made to run with ease.

In order to adjust the several presses relatively to each other and to the work to be accomplished we provide screws R, each of which is swiveled to a stationary part of the base B and tapped into a proper part of the frame of the respective press. The screws f of the bosses D and rod or bar E are loosened, and the screws R properly rotated until the several presses are set or adjusted. The screws f are then tightened, and the several presses are ready to operate in unison as one press.

Power is applied to the shaft C in any desirable manner, and thereby communicated to the pinion a. Simultaneously therewith the boss D, which is suspended freely from the wrist-pin of the wheel b, is rotated and carries with it the rod or bar E, and motion is transmitted to the other bosses, and consequently to the wheels b' b''. The upper pinions also immediately rotate by the action of the pinions a a' a'', and thus the several presses are set in motion, the forms are inked, and the paper or material to be printed, resting on the platens of the presses and receiving an intermittent motion, has the different colors successively printed upon it.

It will be seen that the connection of the wheels b b' b'' by the rod or bar E and bosses D causes said wheels to rotate in harmony and uniformity, their motion being furthermore 40 steadied by the arms F, wheels G G'', and connecting-rod H, and thus the work of the presses is regular, systematical, and steady, and admirable results are obtained.

Having thus described our invention, what 45 we claim as new, and desire to secure by Letters Patent, is—

1. In a printing-machine, the platen having at its rear side laterally and rearwardly extending angular arms, in combination with arms 50 attached to said rearward extensions and supporting the bed, all substantially as and for the purpose set forth.

2. The movable foot or roller support M, in combination with the bed of a printing-press 55 and an inking roller or rollers, substantially as set forth.

3. The wheels having wrist-pins e, in combination with the bar operating the same, the adjustable presses driven by said bar, and the 60 adjustable bosses, substantially as set forth.

4. In combination with a series of presses, the wheels b b' b'', the crank-bar E, the arms F, wheels G G'', and connecting-rod H, substantially as and for the purpose set forth.

IRA ROBBINS.
DAVID HESTON.
